UNITED STATES PATENT OFFICE.

EDWARD FETTER, OF BALTIMORE, MARYLAND.

TUBE AND FLAP.

Application filed August 18, 1924. Serial No. 732,679.

To all whom it may concern:

Be it known that I, EDWARD FETTER, a citizen of the United States of America, residing in the city of Baltimore, State of Maryland, have invented certain new and useful Improvements in Tubes and Flaps, of which the following is a specification.

The difficulties incident to placing the flap in mounting pneumatic tires, particularly with the clincher rim and in instances when the flap has become worn and more or less distorted and wrinkled, are well understood. While these difficulties are greater with the clincher rim, which is ordinarily not collapsible, so that the casing must be stretched over the rim, they are also present and of considerable importance in mounting straight side tires, in which operation the rim is collapsed, so that the tire goes on with much less difficulty. However, when the rim is expanded inside the tire preparatory to locking, there is some difficulty incident to the longitudinal motion or sliding of the strip relatively to the rim or vice versa.

While the flap is in some instances omitted, it is of particular importance with the clincher rim with which it is most difficult to handle on account of the tendency of the tire beads which fit inside the rim to rock and pinch the inner tube.

It is also of interest in the present instance that even though the insertion of the flap may involve no unusual difficulty, this is in accordance with the present practice a separate operation following the insertion of the tube, and that by applicant's improvement it is made possible to insert the tube and flap simultaneously, thereby dispensing with an operation which has been considered essential to the mounting of a pneumatic tire.

The improved structure consists in an inner tube for automobile tires provided with a series of transverse straps or loops extending across the inner surface opposite the tread and spaced apart in the direction of the length or long circumference of the tube, the straps being secured to the tube at the ends and free from the tube throughout the entire intermediate portion which is of a width equal to the width of the flap.

The straps may be of rubber or rubber and fabric or of fabric and other suitable material, and are preferably secured to the tube by vulcanizing, the straps being placed

in the mold with the tube when the tube is vulcanized in the regular course of manufacture, a suitable non-adhesive member being placed on the tube between the ends of the strap to prevent the adherence of the central portion of the strap to the tube.

The straps or loops thus formed serve as means for securing the flap to the tube. In mounting the flap is first threaded through the loops, the tubes being partially inflated, and the tube and flap thus assembled are placed in the casing much more conveniently and quickly than they can be inserted separately but almost as easily and quickly as either the tube or the flap alone could be placed in the casing. The straps, however, not only serve in the capacity of combining the insertion of the tube and flap in a single operation, but they serve to hold the flap in position and prevent its displacement during the mounting of the casing on the rim, and at all times prior to the replacement of the tire. It is also of interest that the flap which covers only the inner peripheral face of the tube need not be removed from the tube in every instance in which the tube is removed from the casing, as for mending punctures and the like, as the majority of punctures are on the tread, and may be located and mended without removing the flap.

In the accompanying drawing I have illustrated a tube provided with flap holding straps in accordance with my invention in the preferred form. I have also shown the improved tube provided with straps assembled with the flap end casing in accordance with my invention.

In the drawings—

Figure 1 is a cross-section through the tube and strap taken at right angles to the length of the tube.

Figure 2 is a transverse section showing a rim, and a casing containing a tube and flap made and assembled in accordance with my invention.

Figure 3 is a side elevation of a tube provided with straps and assembled with a flap, a fragment of the casing and rim being shown in section, and a fragment of felly and spoke in elevation, taken on the line 3, 3 of Figure 2.

Referring to the drawings by numerals, each of which is used to indicate the same or similar parts in the different figures, the inner tube 1 illustrated, may be of the usual

and common type used as a flexible air chamber inside the shoe or casing of a pneumatic tire for road vehicles. The tread surface of the tube or the surface which underlies the tread of the casing is indicated by reference character 2, and the inner peripheral surface by reference character 3. The tube, as shown, and in the preferred form of the invention, is provided with a series of transverse straps 4 or loops 4 formed of straps extending across the inner peripheral face of the tube and secured at each end 5 to the tube wall by vulcanizing or in any preferred way, the intermediate portion 6 of the strap being free and separate from the wall of the tube.

As pointed out in the general statement of the invention, the straps may be of rubber or fabric or fabric and rubber, or any suitable and available material, and they may be most conveniently affixed to the tube by placing them in the molds and vulcanizing them to the tube when the tubing is vulcanized in the regular process of manufacture and before it is cut into lengths and spliced together at the ends to make a ring tube as ordinarily used.

The flap 7 may be of the regular type generally employed to protect the inner surface of the tube from the tire beads and rim, one frequent source of failure of tubes being due to the rocking of the beads, which in the absence of a suitable flap causes the tube to crease and enter between the edges of the bead and the rim, being pinched and broken in this way.

The flap 7 may in the present instance be composed of rubber or fabric and rubber, or any available material.

In mounting the tire or assembling the tube casing and flap on the rim, the tube being partially inflated, the flap, which has its ends free instead of being joined to form a ring as the flap is formed in some instances at the present time, is threaded through the loops 4 between the loops and the inner peripheral face 3 of the tube, and is laid smoothly against the tube in this way, the ends of the flap being overlapped within the casing. The casing 8 with the tube and flap therein is then passed over the rim 9 and the beads 10 of the casing are seated in the grooves 11 formed within the curved edges 12 of the rim, and the parts being suitably arranged, the tube is then inflated, giving the tire the necessary internal pressure to resist and support the load.

By assembling the tube and flap in this way, I not only save the separate operation of inserting the flap but facilitate placing of the latter, avoiding displacement and distortion of the flap when the tire is passed over the rim, and by preventing displacement of the flap, I not only facilitate the mounting of the tire, but prevent injury to the tube resulting from the displacement of the flap.

I have thus described specifically and in detail an improved inner tube in accordance with my invention and the combination of such a tube with a flap and casing combined in accordance with the preferred form of my invention, the description being specific and in detail in order that the nature and operation of the invention may be clearly understood; however, the specific terms herein are used descriptively rather than in a limiting sense, the scope of the invention being defined in the claims.

What I claim and desire to secure by Letters Patent is:

1. An inner tube for pneumatic tires having transverse straps secured to the tube forming loops extending across the inner peripheral face of the tube adapted to receive and hold a flap.
2. The combination with an inner tube for pneumatic tires of a protective flap and means other than the casing and rim for detachably securing the same to the tube and covering its inner peripheral face.
3. The combination with an inner tube for pneumatic tires of a protective flap secured to the tube and covering its inner peripheral face by a plurality of transverse straps spanning the flap and secured at each end to the walls of the tube.
4. An inner tube for pneumatic tires having transverse straps extending across the tube from side to side in the direction of the short diameter of the tube the straps forming loops to receive and hold a protecting flap.
5. The combination with an inner tube for pneumatic tires of a protective strip of rubber, and means detachably securing the same to the inner peripheral face of the tube.

Signed by me at Baltimore, Maryland, this 15 day of August, 1924.

EDWARD FETTER
